US00D794064S

(12) **United States Design Patent** (10) **Patent No.:** **US D794,064 S**
Clymer et al. (45) **Date of Patent:** **** Aug. 8, 2017**

(54) **DISPLAY SCREEN OR PORTION THEREOF WITH GRAPHICAL USER INTERFACE**

(71) Applicant: **Lutron Electronics Co., Inc.**,
Coopersburg, PA (US)

(72) Inventors: **Erica L. Clymer**, Northampton, PA
(US); **Shannon M. Sullivan**,
Coopersburg, PA (US)

(73) Assignee: **Lutron Electronics Co., Inc.**,
Coopersburg, PA (US)

(**) Term: **15 Years**

(21) Appl. No.: **29/564,590**

(22) Filed: **May 13, 2016**

(51) LOC (10) Cl. **14-04**

(52) U.S. Cl.

USPC **D14/488**; D14/492; D14/495

(58) **Field of Classification Search**

USPC D14/485-495

CPC G06F 3/04817; G06F 3/0482

See application file for complete search history.

(57) **CLAIM**

The ornamental design for a display screen or portion thereof with graphical user interface, as shown and described.

DESCRIPTION

The sole FIGURE shows a display screen or portion thereof with graphical user interface showing our new design.

The peripheral dashed broken lines represent a display screen or portion thereof, and form no part of the claimed design.

The dashed broken line bracket unites a group of graphical user interfaces; the dashed broken line bracket forms no part of the claimed design. The group of graphical user interfaces is arranged as shown for convenience of illustration; the arrangement of graphical user interfaces forms no part of the claimed design.

1 Claim, 1 Drawing Sheet
